UNITED STATES PATENT OFFICE.

MICHAEL J. SCANLON, OF DOVER, DELAWARE.

IMPULSE-TURBINE.

No. 909,684.

Specification of Letters Patent.

Patented Jan. 12, 1909.

Application filed October 12, 1905. Serial No. 282,518.

To all whom it may concern:

Be it known that I, MICHAEL J. SCANLON, a citizen of the United States, residing at Dover, in the county of Kent and State of Delaware, have invented new and useful Improvements in Impulse-Turbines, of which the following is a specification.

This invention relates to impulse turbines, and the primary object of the same is to provide a turbine of this class having a superior operation and provided with means whereby the motive fluid is thrown out from the center by the rotation of an impulse drum against motion augmenting devices connected up to the shaft of the drum and operated by the motive fluid thrown out towards the periphery of the drum, the turbine operating as a source of power for driving mechanisms of various forms.

20 A further object of the invention is to provide an impulse turbine having a comparatively simple construction and effective operation and of a strong and durable nature.

In the drawings: Figure 1 is a side elevation, partially in section, of a turbine embodying the features of the invention. Fig. 2 is a top plan view of the impulse drum.

Similar characters of reference are employed to indicate corresponding parts in the views.

The numeral 1 designates the impulse drum provided with a central chamber 2 having curvilinear walls 3 and 4 which are braced and held in adjusted position by radially arranged bars 5 extending outwardly to the periphery of the drum. The chamber has a closed top 2^a and a bottom 2^b also closed except where a depending feed-suction pipe 6 communicates therewith at the center, the said pipe being open and connecting at its lower extremity with a suitable motive fluid supply. The impulse drum 1 is rotatably supported within a frame 7 through the medium of a vertically extending shaft 8 mounted at its lower end in a bearing 9 carried by the closed bottom of the said frame 7, the shaft at its upper extremity within the frame 7 being provided with a beveled gear 11 fixed to the top of the said frame. The upper end of the shaft projecting through the top of the frame 7 has a band pulley 12 fixed thereon from which motion may be transmitted to mechanism to be driven. The drum 1 between the peripheral wall thereof and the walls 3 and 4 is hollow as at 13 and 14, and open at the bottom as shown by Fig.

1; and arranged at opposite ends of the hollow spaces 13 and 14 are vertically extending shafts 15 and 16 supported at their lower ends upon brackets 17 radially projecting outwardly from the bottom 2^b of the chamber 2, the shafts 15 and 16 at their upper ends extending through horizontal arms of brackets 18 and carrying beveled pinions 19, the latter being held in continual mesh with gears 20 fixed on the opposite ends of a horizontal or counter-shaft 21 having bearings at opposite extremities in vertical members of the said brackets 18. The shaft 21 also carries a beveled pinion 22 held in continual mesh with the pinion 11 fixed to the top 10 of the frame 7.

The bottom portions of the hollow spaces 13 and 14 are fully open so that the motive fluid contents thereof may fall into a fixed 75 collecting receptacle 29^a held on the bottom of the frame 7 and having a train of outlet pipes 29. Each of the shafts 15 and 16 carries an impulse wheel 23 horizontally disposed and having outwardly projecting 80 blades, each of the said impulse wheels being disposed in operative relation with respect to a nozzle 24 located at the ends of the chambers 13 and 14 adjacent to the said impulse wheels. These nozzles are in opposed 85 positions in their respective spaces 13 and 14, the said spaces constituting outlet chambers for the relief of the chamber 2, the communication between the latter chamber and the spaces or outlet chambers 13 and 14 being 90 effected through the nozzles 24. Two impact wheels, one on each shaft 15 and 16, are shown to demonstrate a practical apparatus, but it will be understood that the number of these wheels may be increased and the number of nozzles correspondingly multiplied.

95 Secured on the bottom of the frame 7 is a stuffing-box 25 for the lower end of the motive fluid supply pipe 6, the stuffing-box surrounding the bearing 9 at the lower end of 100 the shaft. Connected to the bottom of the frame 7, as at 26, is a cut-off 27 consisting of a suitable valve, and communicating therewith is a motive fluid supply pipe 28. It will be understood that when the cut-off 27 is opened the motive fluid may pass from the pipe 28 upwardly through the stuffing-box, the latter being tubular or hollow, into the feed pipe 6. When the cut-off is closed, the supply of motive fluid to the turbine will 105 be interrupted, as will be appreciated.

110 The operation of the turbine as shown by

Figs. 1 and 2 is as follows: The motive fluid passing into the chamber 2 will be thrown out and act upon the curvilinear walls 3 and 4 and be directed by the latter 5 in reverse directions towards the nozzles 24, and the discharge of the fluid through the nozzles will effect a rotation of the impulse drum 1 after the manner of the operation of a Hero's fountain, and the fluid passing 10 through the nozzles 24 will be directed against the impulse wheels 23, thus breaking up the fluid current or force of the fluid and preventing obstructive action of said fluid that might ensue if it was permitted to pass 15 freely outside of the chamber 2 towards the ends of the spaces 13 and 14 opposite the ends of said spaces at which the nozzles are located. The drum 1 will be rotated as the motive fluid is regularly thrown out towards 20 the walls 3 and 4 and forcefully escapes through the nozzles 24 against the impulse wheels 23.

It will be observed that the incoming motive fluid under pressure has but two outlets 25 from the chamber 2, namely, through the nozzles 24, and as these nozzles are materially reduced as compared to the capacity of the chamber 2, the force of the fluid escaping through the nozzles will set up sufficient 30 momentum with relation to the impulse drum 1 to rotate the shaft 8 with considerable power. A uniformity of rotation of the impulse wheels 23 is maintained by intergearing the said wheels with the shaft 35 21 and the pinion 11, as hereinbefore explained, and the motive fluid after having been deprived of its force falls into the col-

lecting receptacle 29* and escapes through the pipe 29.

It will be evident from the foregoing construction that the shaft 8 can be operated with power advantages which will be dependent upon the initial force or pressure of the motive fluid entering the turbine.

Having thus described the invention, what 45 is claimed as new, is:

An impulse turbine comprising an inclosing frame, a shaft extending therethrough and rotatable therein, an impulse drum fixed on the shaft and provided with a central 50 fluid receiving chamber having a depending feed pipe and opposite curvilinear walls, the drum between the said walls and its periphery being formed with outlet chambers having a nozzle at one end of each communicating with the said central chamber, the two nozzles being in reverse positions, impulse wheels in the ends of the outlet chambers adjacent to the nozzles, the bottoms of the outlet chambers being open, a collecting 55 60 receptacle below the drum and its outlet chambers, gearing for rendering the operation of the impulse wheels uniform, other gear devices for transmitting the motion of said gearing to the drum, and means for controlling the supply of a motive fluid to the drum.

In testimony whereof I have hereunto set my hand in presence of two subscribing witnesses.

MICHAEL J. SCANLON.
